DESIGN FOR A DRESS

Harry Goldman, New York, N. Y.

Application March 25, 1938, Serial No. 76,084

Term of patent 3½ years

To all whom it may concern:

Be it known that I, Harry Goldman, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

Figure 3 is a fragmentary front view of the

dress shown in Figure 1, showing the collar in an open position.

The characteristic feature of my design resides in the combination on the dress disclosed, of the blouse section which is form-fitted in front and bloused in the rear, in combination with the arrangement of the collar edge, front yoke and sleeve darts appearing in even formation, as shown.

I claim:

The ornamental design for a dress, substantially as shown, and described.

HARRY GOLDMAN.
